FLUID PUMP

George T. Downey, Corry, Pa., assignor to Aero Supply Mfg. Co. Inc., Corry, Pa.

Application April 2, 1941, Serial No. 386,542

11 Claims. (Cl. 103—129)

This invention relates to fluid pumps.

An object of this invention is to provide a pump including a rotary pumping element wherein the element is formed of correlated pumping members movable one relative to the other during the rotation of both members, so as to provide for alternate intake and exhaust of the fluid.

Another object of this invention is to provide in a pump of this kind an improved arrangement of the intake and exhaust passages so as to provide a cyclic action during the rotation of the rotary parts.

A further object of this invention is to provide a pump of this kind in which the rotor elements are moved relative to each other by means of intermeshing eccentrically arranged gears providing a smooth positive rotary action, which will eliminate vibration.

A further object of this invention is to provide in a rotary pump a cast pump body or housing and an improved port forming liner for the rotor, the liner being provided with circumferentially arranged elongated ports with certain of the ports communicating with each other and also with an outlet or inlet port.

A further object of this invention is to provide in a pump of this kind an insertible liner having a plurality of superposed circumferentially arranged inwardly facing elongated fluid passages disposed in circumferentially arranged pairs with one passage of each pair in communication, either directly or indirectly, with an inlet port and the other passage of each pair in communication, either directly or indirectly, with an outlet port.

A further object of this kind is to provide in a pump, rotary pumping members and gear means for effecting a relatively quick movement of said members relative to each other during one suction and exhaust cycle thereof coactive with the rotation of said members as a unit and a retarded movement of said members in another cycle thereof.

To the foregoing objects and to others which may hereinafter appear, the invention consists of the novel construction, combination and arrangement of parts as will be more specifically referred to and illustrated in the accompanying drawings, wherein are shown embodiments of the invention, but it is to be understood that changes, variations and modifications may be resorted to which fall within the scope of the invention as claimed.

In the drawings:

Figure 1 is a vertical section taken through a

fluid pump constructed according to an embodiment of this invention.

Figure 2 is a sectional view taken on the line 2—2 of Figure 1.

Figure 3 is a sectional view taken on the line 3—3 of Figure 1.

Figure 4 is a sectional view taken on the line 4—4 of Figure 1.

Figure 5 is a sectional view taken on the line 5—5 of Figure 1.

Figure 6 is a fragmentary sectional view taken on the line 6—6 of Figure 1.

Figure 7 is a plan view of the liner in extended form.

Figure 8 is a plan view of the rotary piston in extended form.

Figure 9 is a top plan of one pair of the pumping blades.

Figure 10 is an end elevation of the structure shown in Figure 9.

Figure 11 is an outer end elevation of one of the other pair of pumping blades showing a portion of the rotor in section.

Figure 12 is a sectional view taken on the line 12—12 of Figure 1.

Figure 13 is a vertical section partly in detail of a modified form of this invention.

Figure 14 is a sectional view taken on the line 14—14 of Figure 13.

Figure 15 is a fragmentary sectional view taken on the line 15—15 of Figure 13.

Figure 16 is a plan view of the liner used with the form shown in Figure 13, the liner being shown in extended form, and

Figure 17 is a plan view of the rotor in extended form which is used with the structure shown in Figure 13.

Referring to the drawings and first to Figures 1 to 12 inclusive, the numeral 20 designates generally a housing which includes a cylindrical body 21 and a gear housing or chamber 22, which extends from one end, and in the present instance the lower or inner end of the cylinder 21. The cylinder 21 is provided with a boss 23 having an intake passage 24 with which an intake pipe 25 is adapted to be threadably connected. The cylinder 21 is also provided with a second boss 26 having an outlet or exhaust passage 27, with which an outlet or exhaust pipe 28 is adapted to be threadably connected. The cylinder 21, as shown in Figure 3, is formed with a relatively long intake opening 29 communicating with the intake port 24 and the cylinder 21 is also provided with a relatively long outlet or exhaust passage 30 communicating with the exhaust port 27.

A cap or head 31 is mounted on the outer or upper end of the cylinder 21 and is provided with an annular flange or rib 32 engaging within the cylinder 21. A sealing gasket 33 is adapted to be interposed between the cap or head 31 and the outer end portion of the cylinder 21. Fastening devices 34 are adapted to removably secure the head 31 on the cylinder 21. The fastening devices 32 are preferably locked against rotation when they are tightened by means of a locking wire 35, which is extended through suitable openings provided in the heads of the fastening members 34.

A liner, generally designated as 36, is fixedly disposed within the cylinder 21 and this liner is of cylindrical construction, but preferably pressed or otherwise firmly held within the cylinder 21. The liner 36 is constructed of metal which may be different in character from the metal or material forming the cylinder 21 and the liner 36 provides a means whereby combined rotation of the pumping structure disposed therein may be alternately placed in communication with the inlet and outlet ports of the cylinder 21. In Figure 7 the liner 36 is shown in extended form in order to more clearly show the various inlet and outlet ports formed therein. As shown in Figure 7, the liner 36 is provided with a plurality of pairs of inlet and outlet openings or passages spaced from each other longitudinally of the liner, the passages being of elongated configuration and extended entirely through the liner 36.

The liner 36 is provided adjacent the upper portion thereof with an elongated outlet passage 37 and an elongated inlet passage 38. The outlet passage 37 is substantially longer than the inlet passage 38, and a dividing wall or partition 39 divides the two adjacent ends of the passages 37 and 38 from each other, whereas a second dividing wall 40 divides the opposite ends of the passages 37 and 38 so as to prevent communication between the two inlet and outlet passages.

A second pair of fluid passages is disposed below the upper passages 37 and 38 and comprise a relatively long inlet passage 41 and a substantially shorter outlet passage 42. The passages 41 and 42 at one end thereof are separated by a dividing wall 43 and at the other end thereof are separated by a dividing wall 44. The upper outlet passage 37 is adapted to communicate with the intermediate outlet passage 42 by means of a communicating passage 45. The upper inlet passage 38 is adapted to communicate with the intermediate inlet passage 41 by means of a communicating passage 46. The communicating passages 45 and 46 are formed as slots in the outer face of the liner 36. A third pair of passages is disposed below the intermediate passages 41 and 42 and comprise a relatively long outlet passage 47 and a substantially shorter inlet passage 48.

The passages 47 and 48 are separated at one end thereof by a partition or dividing wall 49 and at the other end thereof are separated by a dividing wall 50. The inlet passage 48 is in communication with the inlet passage 41 through a communicating slot or passage 51 formed in the outer face of the liner 36 and the outlet passage 47 is in communication with the outlet passage 42 by means of a communicating passage 52 formed in the outer face of the cylinder 36 between the wall 43 and the wall 49. The communicating passage 51 is positioned between the wall 44 and the wall 50.

A lower pair of fluid passages 53 and 54 is disposed below the passages 47 and 48, the passage 75

53 being a substantially long inlet passage and the passage 54 being a substantially shorter but elongated outlet passage. The inlet passage 53 is in communication with the inlet passage 48 by means of a communicating passage 55, and the passage 54 is in communication with the passage 41 by a communicating passage 56. The communicating passages 55 and 56 are formed as slots in the outer face of the liner 36. The inlet passage 41 is disposed in registry with the inlet port 29 and the outlet passage 42 is in registry with the outlet port 30. The inlet and outlet passages 41 and 42 are of substantially greater length than the inlet and outlet ports 29 and 30 respectively, as shown in Figure 7.

As shown in Figure 7 the arrangement of the long inlet and outlet passages in the liner 36 is such that a long outlet passage will extend partly over the entire length of a lower or succeeding outlet passage and will extend partly or substantially for one-half the length of a lower inlet passage. In like manner the long lower inlet passage such as passage 41 extends substantially over the entire length of the upper inlet passage 38 and extends substantially one-half of the length of the next succeeding lower inlet passage 48. By staggering the positions of the pairs of inlet and outlet passages, it is possible to provide a rotor pump structure, to be hereinafter described, which will include a rotary piston and also include rotary pumping blades for alternately exhausting and drawing in the fluids through the inlet and outlet passages.

The liner 36 is adapted at its inner or lower end 35 to seat on the lower or inner end 57 of the cylinder 21, and the upper or outer end of the liner 36 is provided with an annular groove 58 within which the rib 32 is adapted to engage. Preferably the liner 36 at its upper or outer end terminates 40 inwardly from the outer end of the cylinder 21 so as to thereby form an annular lubricant duct or channel 59.

A rotary piston, generally designated as 60, is rotatably disposed within the interior of the liner 36 and includes a cylindrical side wall 61, a flat inner head or wall 62 and a disc-shaped outer wall or head 63. The cylindrical side wall 61 is formed with an inwardly facing groove or rabbet 64 within which the head 63 is adapted to seat. The inner head 62 is provided with a downwardly extending socket member 65, which is formed with a cylindrical outer surface and with a nut socket 66, the purpose for which will be hereinafter described.

The cylinder 60 has fixedly mounted therein a pair of diametrically opposed blades, generally designated as 67 and 68. The blades 67 and 68 are of like construction and extend from the inner to the outer end of the cylindrical side wall 61 of the piston 60. In transverse section the blades 67 and 68 are of sector shape and include a pair of inwardly convergent side walls 69 and 70, which are flat and the blades 67 and 68 also include flat upper and lower walls 71 and 72 respectively. The blades 67 and 68 are fixedly secured to the bottom wall or head 62 of the piston 60 by means of a holding pin 73 which is fixedly mounted in a boss or bushing 74, which extends upwardly from and formed integral with the bottom wall 72. The pin 73 projects downwardly below the bottom wall 72 and engages in an opening 75 formed in the inner head 62. The blade 67 is also formed with an inner transversely arcuate wall 76. The outer ends of the side walls 69 and 70 of the blade 67 are formed with opposed flanges

71 and 78 respectively, which are adapted to snugly engage within the inner surface of the cylindrical side wall 61.

The blade 67 is formed adjacent the upper portion of the side wall 69 with a passage 79 and the side wall 70 is formed adjacent the lower end thereof with a passage 80. The passage 79 is disposed in a position for registry with the upper pair of passages 37 and 38, and the lower passage 80 of the blade 67 is disposed in a position for registry with the lower pair of elongated liner passages 53 and 54. The blade 68 is similar in every detail to the blade 67, with the exception that the blade 68 is formed with passages similar to the passages 79 and 80, which are adapted to register with the elongated passages 41 and 42 and the passages 47 and 48. The cylindrical side wall 61 of the piston 60 is provided with an upper opening 81 adapted to register with the passage 79 of the blade 67 and is also provided with a lower opening 82 disposed in registry with the passage 80. The side wall 61 is also provided with a pair of intermediate openings 83 and 84 adapted to register with side openings provided in the blade 68 similar to the passages 79 and 80 of the blade 67.

A pair of rotary pumping blades generally designated as 85 and 86 are disposed within the piston 60 between the blades 67 and 68. The rotary blades 85 and 86 are of like construction and as shown in Figure 9, are each of sector-shape in transverse section and include inwardly convergent flat side walls 87 and 88 and flat top and bottom walls 89 and 90. A pair of opposed flanges 91 and 92 are carried by the side walls 87 and 88. Each rotary blade is also provided with a transversely arcuate inner wall 93, which is adapted to engage against a cylindrical shaft or sleeve 94. The two rotary blades 85 and 86 are fixedly secured to the sleeve or hollow shaft 94 by means of a pair of horizontally disposed bolts or fastening members 95, which extend through enlargements 96 formed between the side walls 87 and 88 and which extend outwardly from the inner wall 93, as shown in Figure 4.

The hollow shaft 94 has formed integral therewith a second hollow shaft 97, which is of smaller diameter than the shaft 94 and extends therefrom into the gear chamber 22. The hollow shaft 97 extends through the socket member 65, as shown in Figure 1, and is of substantially smaller diameter than the interior of the nut socket 66. A drive shaft 98 is disposed concentrically of the hollow shaft members 94 and 97 and is provided with a pair of enlargements 99 and 100 through which the bolts or fastening members 95 engage, so that the sleeve shaft 94 will rotate as a unit with the drive shaft 98. The enlargements 99 and 100 are annular in transverse section and are spaced apart along the shaft 98 being positioned entirely within the sleeve shaft 94, as shown in Figure 1. The drive shaft 98 is substantially longer than the sleeve shaft 97 and is provided with an extension 101 which, as shown in Figure 12, is square in transverse section and a splined coupling member 102 is mounted on the square shaft member 101 being secured thereon by means of a holding nut 103 which is threadably mounted on a threaded stud 104 carried by the square shaft 101.

The splined coupling member 102 is positioned exteriorly of the gear chamber 22 and provides a means whereby the drive shaft 98 may be detachably coupled with a suitable driving means. The driving means may be in the form of a small mo-

tor or may be in the form of a driving connection with an internal combustion engine, such as an aeroplane engine or the like.

The head 63 is provided with an axial stud 105 which rotatably engages in a socket or recess 106 formed in the outer or upper end of the enlargement 100, as shown in Figure 1. The head 63 is also provided with a second stud 107, which is substantially smaller in diameter than the stud 105 and the stud 107 is mounted in an inner anti-friction race member 108.

The cap or head member 31 is provided with an outwardly or upwardly offset bushing 109 within which the outer race 110 of an anti-friction bearing is snugly positioned. Anti-friction balls 111 engage between the two race members 108 and 110. The anti-friction bearing structure including the race members 108, 110 and the balls 111 provides a means for rotatably supporting the outer or upper end of the rotary piston 68 within the liner 36.

The gear chamber 22 extends inwardly or downwardly from the cylinder 21 and is of smaller diameter or size than the cylinder 21, being formed with a side wall structure 112, which extends from the inner wall 57 of the cylinder 21 and also includes an inner wall or head 113. The head 113 in the present instance is formed integral with the side wall 112 and a flange 114 extends outwardly from the head or inner wall 113. The upper or inner end of the gear chamber 22 has positioned therein a plate or head 115, which may be pressed or otherwise tightly disposed in the interior of the gear chamber 22. The plate or head 115 is provided with an opening 116 therethrough and within which the hollow shaft 65 rotatably engages.

A flanged gasket 117 is preferably interposed between the sleeve 66 and the wall of the opening 116, the flange 118 of the gasket 117 engaging on the upper surface of the head 115 and between the head 115 and the inner wall or head 62 of the piston 60. In this manner the flange 118 forms a lubricant passage 119 between the head 62 and the head or plate 115. A cylindrical bushing or sleeve 120 is snugly mounted in an opening 121 formed in the head 113 and the lower end of the sleeve shaft 97 is adapted to rotatably engage within the sleeve or bearing member 120. The bearing member 120 at its inner end is provided with a flange 122, which engages against the inner side of the head 113 and prevents the outward movement of the bearing sleeve 120.

A driving gear 123 is fixedly mounted on the sleeve shaft 97 above the bushing 20, the sleeve shaft 97 being provided with flattened surfaces, which are engaged by the gear 123 so as to hold the gear 123 against rotation relative to the sleeve shaft 97. The shaft 97 engages through the gear 123 at one side of the axial center of the gear 123, as shown in Figures 1 and 6. The gear 123 meshes with a gear 124, which is fixedly secured as by a key 125 to a jack shaft 126. The shaft 126 is provided with an eccentrically disposed annular gear shaft 127 on which the gear 124 is fixedly mounted. The eccentric shaft member 127 is also positioned eccentrically of the axial center of the gear member 124 so that upon rotation of the driving gear 123 the gear 124 will be in constant mesh with the gear 123.

A second gear 128 is mounted on an offset shaft or crank member 129, carried by the jack shaft 126, and the gear member 128 is fixedly secured to the offset shaft member 129 by means of a key 130. A sleeve member 131 is rotatably mount-

ed on the sleeve shaft 97 and is provided with a pair of nut members 132 and 133. The nut member 133 engages within the nut socket 66 so that the sleeve 131 will be held against rotation relative to the sleeve member 65 and the piston 60. A gear member 134 is mounted on the nut member 132, being disposed with the axial center offset with respect to the axial center of the sleeve 131. The gear 134 is in constant mesh with the gear 128 so that rotation of the gear 128 will effect the rotation of the piston 60.

By providing the intermeshing pairs of eccentrically disposed driving gears for the piston 60, the piston 60 is given a plurality of different speeds during each complete rotation thereof so that the effect of this variation in the speed of the rotation of the piston or rotor 60 is to constitute the blades 67 and 68 oscillatory blades which oscillate back and forth with respect to the rotary blades 85 and 86 carried by the rotary sleeve shaft 94.

The lower end of the jack shaft 126 is mounted in an inner anti-friction race member 135 and an outer anti-friction race member 136 is snugly mounted in a recess 137 formed in the head 113. Anti-friction balls 138 are interposed between the two race members 135 and 136. The opposite or inner end of the jack shaft 126 is mounted in an inner race member 139, and an outer race member 140 is mounted in a recess or socket 141, which is formed in the plate or inner head 115. Anti-friction balls 142 are interposed between the race members 139 and 140. The two gears 123 and 134 are held in spaced apart relation by means of a washer 143, which engages about the sleeve shaft 97. By providing the two nut members 132 and 133 on the sleeve shaft 91 a flange or rib 144 is formed on the sleeve 131 against which the inner side of the gear 134 is adapted to abut.

The gears hereinbefore described are rotatably mounted in a combined gear and lubricant chamber 145. The chamber 22 has leading off therefrom an outlet passage 146, and a needle valve member 147 is adapted to engage adjacent the outer end of the outlet passage 146 so as to regulate the amount of lubricant flowing out of the passage 146. The needle valve member 147 is threaded into a threaded bushing 148, which engages in the wall of the chamber 22, and a lock nut 149 is threaded onto the needle valve member 147 so as to tightly hold the valve member 147 in adjusted position.

The outlet passage 146 communicates with an enlarged lubricant chamber 150 and a downwardly extending passage 151 communicates at its upper end with the passage or chamber 150. An inwardly extending passage 152 extends from the passage 151 and communicates with an opening 153 formed in the bushing 129, so that the lower portion of the sleeve shaft 97 will receive adequate lubricant. An upwardly extending lubricant passage 155 extends from the chamber 150 and communicates with an outwardly or laterally extending passage 156. An upwardly extending passage 157 is formed in an offset housing member 158 and extends upwardly to and opens into a slot 159, which may be formed in the gasket 33 so that the lubricant from the passage 157 will flow through the slot 159 into the lubricant passage 59.

The liner 36 is provided with a downwardly extending lubricant passage 160 which at its upper end communicates with the passage 59 and a pair of inwardly extending branches or passages 161

and 162 extend inwardly through the liner 36 and communicate with the inner annular grooves 163 and 164 respectively, which are formed in the liner 36 between the upper pairs of inlet and outlet ports. The liner 36 may also be provided with an inwardly extending opening or lubricant passage 165 communicating with the upper portion of the vertical channel or passage 160, so that the upper portion of the rotor 60 will receive proper lubricant.

The upper or outer head 63 of the rotor 60 is spaced from the outer head 31 of the housing 20, thereby providing an outer lubricant chamber 166, which communicates with the lateral passage 165 and also communicates with the anti-friction bearing comprising the race members 108 and 110 and the balls 111. Preferably the bushing or boss 109 is formed with a lubricant chamber 167 outwardly of the anti-friction bearing and the two studs 105 and 107 are formed with a common axial lubricant passage 168.

The lubricant from the chamber 167 is adapted to flow downwardly or inwardly through the passage 168 and engage in a lubricant chamber 169 formed in the shaft enlargement 100 inwardly from the inner stud shaft 105. The enlargement 100 is provided with a plurality of radially arranged openings 170 leading from the lubricant chamber 169, which register with lubricant openings 171 formed in the sleeve shaft 94. The inner walls 93 of the rotary blades 85 and 86 are formed with an inner lubricant passage 172, which communicates with the horizontal passage 171. The upper end of the passage 172 communicates with a groove 173 formed in the upper wall 99, and a pair of outwardly divergent grooves 174 communicate with the groove 173 and extend parallel with the side walls of the rotary blades 85 and 86.

The outer ends of the blades 85 and 86 are formed with outer lubricating grooves 175 communicating with the upper grooves 174 so that the outer flanges 91 and 92 will receive proper lubricant. The outer vertical lubricant grooves or passages 175 connect with inwardly convergent grooves 176 formed in the bottom walls of the rotary members, and the lower grooves 176 communicate with the lower ends of the vertical grooves or channels 172 by a connecting groove similar to the groove 173.

The liner 36 is also formed with a vertical lubricant duct or channel 177, which extends from substantially the longitudinal center of the liner 36 to the lower end thereof. The channel 177 communicates at its upper end with an inwardly extending opening 178, which also communicates with the annular groove 164. A second inwardly extending opening 179 communicates at one end with the vertical passage 177 and at its other or inner end communicates with an annular groove 180 formed in the liner 36 below the groove 164 and between the passages 47, 48 and the passages 53 and 54.

The passage 177 at its lower end communicates through a slot 181 with the lower lubricant chamber 119. The lubricant in the chamber 119 is adapted to return to the reservoir 145 through the anti-friction bearing including the race members 139 and 140 and the balls 142. The cap or head 31 is provided with an upstanding boss 182 having a threaded recess 183, so that a supporting means may be threaded into the boss 182 for supporting the housing 20 in the desired position.

In Figures 13 to 17 inclusive, there is disclosed another form of fluid pump assembly, which

includes a pump housing and rotary piston with pumping blades therein similar in substantially every detail to the rotary piston, shown in Figures 1 to 13 inclusive. In this form there is provided a pump housing, generally designated as 184, which includes a cylinder 185 and a gear housing 186, which extends downwardly from the cylinder 185. The cylinder 185 has mounted therein a cylindrical liner 187, which is substantially similar in every detail to the liner 36, being provided with pairs of superposed fluid openings or passages which extend therethrough. The housing 184 is provided with a pair of bosses 188 and 189 having intake and outlet ports 190 and 191 respectively, which communicate with arcuate intake and outlet ports 192 and 193 extending partly about the cylinder 185.

The liner 187 is provided with an upper elongated outlet port 194 and an elongated inlet port 195, the latter port being substantially shorter in length than the outlet port 194. The liner 187 is also provided with a second pair of ports below the upper ports 194 and 195, the second pair of ports includes an elongated inlet port 196 and an elongated outlet port 197, the latter port being substantially shorter in length than the inlet port 196. The outlet port 197 is in registry with the outlet port 193, but as shown in Figure 16, the elongated liner port 197 is substantially longer than the outlet port 193. A third pair of fluid ports is disposed below the ports 196 and 197, the third pair of ports including elongated outlet port 198 and an elongated inlet port 199. The inlet port 199 is substantially shorter in length than the outlet port 198.

A lower pair of ports is provided in the liner 187 and includes a lower elongated inlet port 200 and a lower outlet port 201, the latter being substantially shorter in length than the inlet port 200.

The outlet port 194 is in communication with the outlet port 197 by a communicating passage 202, which is formed in the outer side of the liner 187 and the upper inlet port 195 is in communication with the next succeeding inlet port 196 by means of a communicating passage 203. The inlet port 196 is in registry with the inlet port 192, but as shown in Figure 16 the inlet port 196 is substantially longer than the port 192. The inlet port 196 is in communication with the relatively short inlet port 199 by means of a communicating passage 204 formed in the outer side of the liner 187, and the outlet port 197 is in communication with the outlet port 198 by means of a communicating passage 205.

The inlet port 199 is in communication with the lower inlet port or passage 200 by means of a communicating passage 206 formed in the outer side of the liner 187 and the outlet passage 198 is in communication with the outlet passage 201 by means of a communicating passage 207 formed in the outer side of the liner 187.

A rotor, generally designated as 208, is rotatably disposed within the liner 187 and includes a cylindrical side wall 209, a bottom wall 210, which is fixed to or formed integral with the cylindrical side wall 209 and also includes a top wall or head 211, which seats in a rabbet or annular recess 212 formed in the upper or outer end portion of the cylindrical side wall 209. The inner wall or head 210 has formed integral therewith or fixed thereto a sleeve or hollow shaft 213, which is formed with an inner nut socket 214.

A pair of diametrically opposed pumping blades 215 and 216 are fixedly mounted within the cylindrical side wall 209, and each blade 215 is of sector configuration in transverse section and is secured to the rotor 208 by means of a holding pin 217, which is mounted in a boss or bushing 218 carried by the bottom wall of each blade 215 and 216. The pin 217 is adapted to engage in the inner wall or head 210 similar to the structure shown in Figure 11. The cylindrical side wall 209 is provided with an upper opening 219 disposed at one side of a fixed blade and is also provided with a lower opening 220 disposed on the opposite side of the same blade. The side wall 209 is also provided with a pair of intermediate openings 221 and 222, which are adapted to be disposed on opposite sides of the other of the stationary blades.

The opening 219 is disposed in position for registry with the upper pair of passages 194 and 195 upon rotation of the rotor 208, and the lower opening 220 is disposed in a position for registry with the lower pair of openings 200 and 201. The intermediate opening 221 is disposed in a position for registry with the intermediate pair of openings 196 and 197 and the second intermediate opening 222 is disposed in a position for registry with the second of the intermediate pair of openings 198 and 199.

A pair of movable pumping blades 223 and 224 are disposed within the cylinder 208 between the blades 215 and 216, and the blades 223 and 224 are fixedly secured to a drive shaft 225 by means of a holding member 226, which engages through bosses 227 and 228 carried by the blades 223 and 224 respectively. The blades 223 and 224 are similar in every detail to the blades 85 and 86, being of sector configuration in transverse section and the flat opposite faces 40 of the blades 223 and 224 are adapted to alternately confront or substantially contact with the opposite flat faces of the blades 215 and 216.

The shaft 225 is provided with a reduced elongated extension 229, which extends downwardly into the gear housing 186. A gear 230 is keyed onto the shaft 229 in the gear housing 186, the gear 230 being eccentric to the shaft 229. A pair of balance weights 231 and 232 are also keyed onto the shaft 229 on opposite sides of the gear 230 and are offset opposite from the gear 230, as shown in Figure 13. The gear 230 is in constant mesh with a gear 233, which is keyed to a jack shaft 234. The jack shaft 234 is rotatably mounted at its upper end in an anti-friction bearing structure 235, which is mounted in an annular plate or head 236, which is seated on a shoulder 237 at the inner end of the cylinder 185. The plate or head 236 provides a partition between the cylinder 185 and the gear housing 186 and also provides a means for rotatably supporting the upper or outer ends of the pair of jack shafts.

A cylindrical sleeve 238 is mounted about the jack shaft 234 and at its upper end bears against the anti-friction bearing 235. Preferably the sleeve 238 is tight on the shaft 234 so that the shaft 234 is thereby held against endwise movement in one direction by contact of the sleeve 238 with the anti-friction bearing 235.

The jack shaft 234 has keyed thereon a pair of balancing weights 239 and 240, which are disposed on opposite sides of the gear 233 and are arranged eccentrically with respect to the shaft 234 opposite from the eccentricity of the gear

233. The jack shaft 234 also has keyed thereon a second gear 241, which is eccentric to the shaft 234 in a position opposite from the eccentricity of the gear 233. A pair of balancing weights 242 and 243 are keyed to the jack shaft 234 on opposite sides of the gear 241 and are eccentric to the shaft 234 in opposed relation to the eccentricity of the gear 241.

The lower end of the jack shaft 234 is rotatably mounted in an anti-friction bearing 244, which is mounted in a lower plate or head 235 seating on a shoulder or seat 246. Preferably the lower end of the shaft 234 is provided with a reduced threaded portion 247 on which a holding nut 248 is threaded. The gear 241 is adapted to mesh with a centrally disposed eccentric driving gear 249, which is eccentrically carried by an auxiliary driving shaft 250. The peripheral surface of the shaft 250 is formed with flat faces, which are engaged by the eccentric driving gear 249.

A pair of balancing weights 251 and 252 are mounted on the shaft member 250 on opposite sides of the eccentric driving gear 249. The lower end portion of the shaft 229 is provided with a reduced stub shaft 253, which rotatably engages in a bushing or sleeve 254 carried by the shaft member 250. The shaft member 250 engages in a hollow shaft 255, which is rotatable in a bearing sleeve 256. The sleeve 256 is snugly mounted in the lower or outer wall or head 257 of the bearing housing 186. The sleeve 255 is provided with a nut socket 258 within which the shaft 250 engages so that the shaft 250 will rotate with the sleeve 255. Preferably a cylindrical packing 259 is mounted on a reduced stub 260 carried by the shaft 250, so as to provide a cushioning means for the lower end of the shaft 250.

A square shaft 261 engages in a nut socket 262 formed in the outer end of the sleeve 255 and a splined coupling member 263 is formed integral with the square shaft 261 and is adapted to be connected to a suitable operating means. The shaft 261 is preferably formed so that it will tightly fit into the nut socket 262 in order that the shaft 261 will be held against endwise movement with respect to the sleeve shaft 255.

An eccentrically disposed gear member 263 is disposed in the gear housing 186 and meshed with the eccentric driving gear 249 diametrically opposite from the gear 241. The gear 263 is keyed to a second jack shaft 264 and a pair of balancing weights 265 and 266 are also keyed to the jack shaft 264 on opposite sides of the gear 263. The lower end of the jack shaft 264 is rotatably mounted in an anti-friction bearing 267, which is seated in a recess 268 formed in the inner plate or head 236. The jack shaft 264 is provided at its lower end with a reduced threaded member 269 on which a holding nut 270 is threaded.

The upper end of the jack shaft 264 is rotatably mounted in an upper anti-friction bearing 271 carried by the partition or head 236. An eccentric gear 272 is keyed to the jack shaft 264 above the gear 263 and a pair of balancing weights 273 and 274 are disposed on opposite sides of the gear 272 and are also keyed to the jack shaft 264.

A rotor driving gear 275 meshes with the eccentric gear 272 and is snugly mounted on a square end 276 of a sleeve shaft 277. The sleeve shaft 277 is provided with an outer flat nut construction which is adapted to engage within

the nut socket 214. A cylindrical bushing 278 is disposed between the inner cylindrical surface of the sleeve 277 and the peripheral surface of the reduced shaft 229. A bearing sleeve 279 is mounted in the plate 236 and the hollow shaft 213 is rotatable within the sleeve or bearing 279. The bearing 279 is provided with a flange 280, which not only holds the sleeve 279 against inward endwise movement, but also acts as a spacing means and a bearing for the rotor 208.

The housing 184 is provided with an upper head or plate 281 having an annular flange or rib 282 engaging in an annular groove 283 formed in the cylinder 185. The head 281 is detachably secured to the cylinder 185 by fastening devices 284. The head 281 is formed centrally thereof with an upwardly offset boss or bushing 285, within which an anti-friction bearing 286 is mounted. The rotor head 211 is provided centrally thereof with a stub shaft 287 which engages the anti-friction bearing 286 so that the rotor 208 will be held concentrically of the cylinder 185. The boss or bushing 285 is provided with a threaded opening 288, which may serve as a means for receiving a threaded supporting member or, if desired may serve as a means for connecting the housing 184 with a source of lubricant supply, which may be discharged into the bushing 285 and be forced through the anti-friction bearing 286 and then downwardly into the gear housing 186. The gear housing 186 is preferably filled with a suitable lubricant, so that the eccentric gears will be lubricated at all times.

In operation, the blades 85 and 86 will rotate at a constant speed whereas the rotor 80 with the blades 87 and 88 will rotate at variable speeds during each complete revolution thereof. These variable speeds are accomplished by the eccentric gearing which in one cycle causes the advance of the blades 87 and 88 until one face of each of such blades substantially contacts with a face of each blade 85 and 86 to thereby exhaust the fluid therebetween. In another cycle the blades 87 and 88 with the rotor 80 are retarded in their rotation, so that the blades 85 and 86 rotate at a greater speed than the blades 87 and 88, and the opposite faces of blades 87 and 88 substantially contact with the opposite faces of blades 85 and 86.

The eccentric gearing also provides an interval between each of the aforesaid cycles when all of the blades rotate as a unit and at the same speed. At these intervals the contacting blades are passing the walls between the inlet and outlet passages of one or more pairs of circumferentially aligned passages.

With the construction shown in Figures 13 to 17, the operation of the blades is similar to the structure shown in Figures 1 to 12, with the exception that the both pairs of blades 215, 216 and 223 and 224 are rotated at variable speeds, the blades 215, 216 being accelerated while the blades 223, 224 are simultaneously retarded in their rotation during one cycle and in another cycle the blades 223, 224 are accelerated while the blades 215, 216 are simultaneously retarded, thus providing the effect of an oscillation of both pairs of blades. Furthermore, by providing eccentric driving gears for both pairs of blades they are given accelerated movement toward and from each other.

With respect to long fluid passages in the liner 36, it might be stated that these are provided in order to provide for the intake and exhaust of

the fluid on that cycle, designated the retarded cycle, wherein the short radius of the driving gear is effecting movement of the rotor, the driving gear at this time retarding the rotation of one pair of blades, as for example retarding the rotation of blades 67 and 68 until the cycle is completed. During this cycle the rotor 60 travels circumferentially a greater distance and thus making it necessary to elongate an inlet and an outlet passage, whereas on the other or accelerated cycle the inlet and outlet passages are much shorter due to the fact that the long radius of the eccentric driving gear is operating on the short radius of the driven eccentric. During the time that the driving gear is working in the accelerated cycle, the exhaust and intake occurs in a shorter circumferential space than for the retarded cycle. The circumferential offsetting of the pairs of superposed passages compensates for the interval between the operating cycles when both pairs of blades are rotating as a unit and prevents leakage of the fluid following the suction stroke.

The overlapping of a short intake passage with a long intake passage, as for example, short passage 38 with long passage 41 provides for an increased port area during the accelerated cycle so that the fluid may be more readily drawn into the cylinder in an equal quantity on the accelerated cycle as on the decelerated cycle. The overlapping of the short and long outlet passages permits the exhausting of the fluid on the accelerated cycle without excessive pressure being exerted on the operating parts.

What I claim is:

1. A fluid pump comprising a housing including a cylinder and a gear chamber, said housing having an inlet and outlet port communicating with said cylinder, a cylindrical liner in said cylinder provided with pairs of elongated fluid passages, said pairs of passages being spaced longitudinally of said liner, one passage of each pair of passages communicating with said inlet port, and the other passage of each pair communicating with said outlet port, a cylindrical piston rotatable in said liner and having a plurality of openings spaced apart circumferentially of said piston, said openings being registerable with said passages, a pair of opposed blades fixed within said piston between said openings, a pair of rotary blades between said fixed blades and movable relative to said piston and said fixed blades for alternately effecting suction within and exhaustion of the fluid from said piston, and gear means in said gear chamber operatively connected with said piston and said rotary blades for rotating said piston at varying speeds while simultaneously rotatating said rotary blades.

2. In a pump having inlet and outlet ports, pairs of relatively movable rotary pumping elements correlated with said ports and having communication therewith, means operatively connected with said elements for effecting operation thereof to thereby provide an accelerated pumping cycle for said elements and a retarded pumping cycle for said elements during each revolution of said elements, and a ported stationary cylindrical member about said elements, said member having series of elongated fluid passages the passages of each series being spaced longitudinally of said liner with respect to the passages of each other series, one passage of each series being substantially longer than the other passage of the same series to thereby provide communication between said ports and said ele-

ments during the retarded cycle, and the shorter passage of each series providing communication between said ports and said elements during the accelerated cycle.

3. In a pump having inlet and outlet ports, pairs of relatively movable rotary pumping elements correlated with said ports, eccentric gear means for effecting operation of said elements to thereby provide alternate accelerated and retarded pumping cycles for said elements during each revolution of said elements, and liner means about said elements for providing communication of said elements with said ports during each cycle thereof, said latter means including a cylindrical member formed with pairs of parallel passages, said pairs of passages being spaced longitudinally of said liner means, and one passage of each pair being longer than the other passage of each pair to thereby provide communication between said ports and said elements during the retarded cycle thereof, the remaining or short passage of each pair providing communication between said ports and said elements during the accelerated cycle thereof.

4. In a pump having inlet and outlet ports, pairs of relatively movable rotary pumping elements correlated with said ports, eccentric gear means for effecting operation of said elements to thereby provide alternate accelerated and retarded pumping cycles for said elements during each revolution of said elements, and liner means about said elements for providing communication of said elements with said ports during each cycle thereof, said latter means including a cylindrical member formed with pairs of parallel passages, said pairs of passages being spaced longitudinally of said liner means, and one passage of each pair being longer than the other passage of each pair to thereby provide communication between said ports and said elements during the retarded cycle thereof, the remaining or short passage of each pair providing communication between said ports and said elements during the accelerated cycle thereof, said member also having means outwardly of said elements for communicating the long passage of one pair with the short passage of an adjacent pair.

5. In a pump, relatively movable rotary pumping elements, and operating means therefor, said operating means including a drive shaft, an eccentrically disposed circular driving gear fixed to said shaft, a pair of jack shafts, a circular eccentrically disposed gear fixed to each jack shaft and meshing with said driving gear, a second circular eccentrically disposed gear fixed to each jack shaft and positioned with the long radius thereof opposite to the long radius of the first jack shaft gear, an eccentric gear operatively connected with certain of said elements and with one of said second jack shaft gears, and an eccentric gear operatively connected with the remaining of said elements and with the other of said second jack shaft gears.

6. A fluid pump comprising a housing having inlet and outlet ports, a cylindrical liner fixed in said housing, said liner being provided with longitudinally spaced apart pairs of elongated openings, one opening of each pair being longer than the other opening and the ends of the openings of each pair being spaced apart and constituting an idler space, said liner having peripheral passages providing communication between a port of each pair and said inlet port and a port of each pair and said outlet port, said liner also

having peripheral passages communicating the long opening of one pair with the short opening of an adjacent pair of openings, one opening of each pair constituting an outlet passage and the other opening of each pair constituting an inlet passage, a cylindrical body rotatable within said liner and formed with an opening for each pair of liner openings, a pair of pumping blades fixed in said body, a second pair of pumping blades movable in said body between said fixed blades, means rotating said body, and means for moving said movable blades relative to said fixed blades.

7. In a pump having inlet and outlet ports, a cylindrical stationary member, pumping means movable in said member, said member having longitudinally spaced apart pairs of elongated openings disposed in parallel relation, one opening of each pair being long and the other opening of each pair being short, alternate ones of said long openings being outlet openings, the remaining ones of said long openings being inlet openings, alternate ones of said short openings being outlet openings, the remaining ones of said short openings being inlet openings, means communicating said outlet openings with each other and with said outlet port, means communicating said inlet openings with each other and with said inlet port, and operating means for said pumping means.

8. In a pump having inlet and outlet ports, a cylindrical stationary member, pumping means movable in said member, said member having longitudinally spaced apart pairs of elongated openings disposed in parallel relation, one opening of each pair being long and the other opening of each pair being short, alternate ones of said long openings being outlet openings, the remaining ones of said long openings being inlet openings, alternate ones of said short openings being outlet openings, the remaining ones of said short openings being inlet openings, means communicating said outlet openings with each other and with said outlet port, means communicating said inlet openings with each other and with said inlet port, and means operating said pumping means to thereby provide alternate accelerated and retarded pumping cycles.

9. In a pump having inlet and outlet ports, a cylindrical stationary member, pumping means movable in said member, said member having longitudinally spaced apart pairs of elongated openings disposed in parallel relation, one opening of each pair being long and the other opening of each pair being short, alternate ones of said long openings being outlet openings, the re-

maining ones of said long openings being inlet openings, alternate ones of said short openings being outlet openings, the remaining ones of said short openings being inlet openings, means communicating said outlet openings with each other and with said outlet port, means communicating said inlet openings with each other and with said inlet port, and means operating said pumping means to provide accelerated pumping cycles when said pumping means is in confronting position to said short openings and to provide retarded pumping cycles when said pumping means is in confronting position to said long openings.

10. In a pump having inlet and outlet ports, a cylindrical stationary member, pumping means movable in said member, said member having longitudinally spaced apart pairs of elongated openings disposed in parallel relation, one opening of each pair being long and the other opening of each pair being short, alternate ones of said long openings being outlet openings, the remaining ones of said long openings being inlet openings, alternate ones of said short openings being outlet openings, the remaining ones of said short openings being inlet openings, a short outlet opening overlapping an adjacent long outlet opening, a short inlet opening overlapping an adjacent long inlet opening, means communicating said outlet openings with each other and with said outlet port, means communicating said inlet openings with each other and with said inlet port, and operating means for said pumping means.

11. A fluid pump comprising a housing having inlet and outlet ports, a liner fixed in said housing having pairs of longitudinally spaced apart passages, one passage of each pair of passages being an outlet passage and the other passage of each pair being an inlet passage, said liner having means communicating the outlet passages with each other and with said outlet port and also having means communicating the inlet passages with each other and with said inlet port, a closed rotor in said liner having openings coplanar with each pair of passages, a pair of pumping blades fixed in said rotor, a second pair of pumping blades in said rotor and movable relative to said fixed blades, means rotating said second pair of blades at a constant speed, and means rotating said rotor at alternate accelerated and retarded cycles to thereby effect movement of said pairs of blades relative to each other, said passages being so arranged circumferentially about said rotor as to register with the openings of said rotor during each cycle of the latter.

GEORGE T. DOWNEY.
